UNITED STATES PATENT OFFICE.

CHARLES MILLER, OF AUBURN, NEW YORK.

HARVESTER.

SPECIFICATION forming part of Letters Patent No. 364,127, dated May 31, 1887.

Application filed March 13, 1886. Serial No. 195,075. (No model.)

To all whom it may concern:

Be it known that I, CHARLES MILLER, a citizen of the United States, and a resident of Auburn, in the county of Cayuga and State of New York, have invented certain new and useful Improvements in Harvesters; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved low-down binder harvester. Fig. 2 is a longitudinal vertical sectional view taken through the binder-platform. Fig. 2 is a similar view, looking in the opposite direction. Fig. 3 is a vertical sectional view taken through the main driving-shaft, looking toward the rear of the machine. Fig. 4 is a top plan view. Fig. 5 is a bottom plan view. Figs. 6, 7, 8, 9, 10, and 11 are detail views of different parts of the machine.

Similar numerals of reference indicate corresponding parts in all the figures.

This invention relates to self-binding harvesters, and more particularly to that class known as "low-down binders." Its object is to produce such a machine as will be prompt and efficient in all its operations, complete in itself, and entirely under the control of the operator.

With these ends in view, it consists in the improved construction and combination of parts, as will be hereinafter more fully described, and particularly pointed out in the claims.

Referring to the accompanying drawings, 1 represents the grain-platform of a harvester provided with the usual cutting apparatus, driving mechanism, rake, and supporting-wheels, and to one side of which my improved binding platform and mechanism are secured. 40 This binding-platform consists of a suitable frame, 2, the under side of which is provided with brace-rods 3 and blocks 4. To the front part of the platform a casting, 5, is secured, having bearings for the horizontal shaft 6, and for the short vertical shaft 7. At the outer end of the shaft 6 a small sprocket-wheel, 8, is secured, which is driven by a

chain, 9, passing around the larger sprocket-wheel, 10, which is secured to the drive-wheel 11. Near the center of the shaft 6 a 55 clutch, 12, is secured, which engages with another clutch upon the side of the bevel-pinion 13, which is loosely journaled upon the shaft. The inner end of the shaft is provided with an annular groove or channel, in which a spring, 14, engages when the binding mechanism is in operation, but which is thrown out of it by the carrier when it returns to its position after a sheaf has been bound. To the inner bearing, 15, of the shaft, which is larger 60 than the other bearings, and which is also provided with bearings for the shaft 7, an arm, 16, is secured, and to the end of which a lever, 17, is pivoted. A rod, 18, is secured to the lower end of the lever 17 and 65 extends to the opposite side of the platform, where it engages with the lever 19, the lower end of which is pivoted to the casting 5. A coiled spring, 20, is secured between the extreme outer end of the rod 18 and the end of 70 the lever 19. The intermediate part of the lever 19 engages with a grooved collar, 21, which is rigidly secured upon the shaft 6. A coiled spring, 22, bears against this collar and also against a ring, 23, which is adjustably secured to one of the bearings of the shaft 6 by means of a slotted arm, 24, the shaft passing through the ring and spring. It will now be seen that when the top of the lever 17 is forced in a direction toward the shaft 6, which is 75 done by the rake when it delivers a gavel of grain to the binding mechanism, the shaft is slipped longitudinally in its bearings until the clutch 12 engages with the clutch upon the side of the pinion 13, which engages with the 80 pinion 25 upon the end of shaft 7 and sets the binding mechanism in motion. The spring 14 then engages with the groove in the end of the shaft and keeps it from slipping back until the sheaf has been bound.

The rear portion of the platform is provided with two brackets, 26 and 27, the tops of which are secured together by means of the beam 28, and they also furnish bearings for the knotter-shaft 29. The knotter-shaft is supplied with any of the well-known knotters now in use, and which it is not necessary to illustrate, as I make no claim to that part of the binding mechanism. Two shafts, 30 and

31, the outer ends of which are provided with intermeshing cogged segments 32 and 33, are suitably journaled across the rear portion of the binding-platform. One of these shafts is 5 provided at its intermediate portion with a compressor-arm, 34, and the other shaft with two curved compressor-arms, 35 and 36, one of which is the needle and carries the thread around the sheaf. Each of these curved arms 10 is provided upon its under side with the rounded projection 36', which engages with the carrier as it advances with a gavel and assists the raising of the arms to a vertical position to retain the sheaf in place while being 15 bound.

An auxiliary compressor, 37, having a groove across its top, or two short parallel pieces, 38, instead, is moved vertically between the shafts 30 and 31 by means of a lever, 39, which is 20 pivoted to the under side of the platform at 40. The opposite end of this lever is connected by the rod 41 to the end of the lever 42, which is pivoted to the top of the bracket 25 and provided with a lug, 43. A cam, 44, secured upon the knotter-shaft, bears against this lug and operates the lever and with it the auxiliary compressor.

One of the cogged segments, 32, is firmly secured upon its shaft 30, while the other one 30 fits loosely upon its shaft and is provided with two arms, 45 and 46, which arms are provided with the pins 47 and 48, respectively. The segment 33 is kept upon its shaft by means of the collar 49, which is firmly secured upon the 35 end of the shaft and is provided with an arm, 50, which is connected to the arm 46 of the segment 33 by means of the hooked rods 51 and 52 and the coiled spring 53. The outer ends of each of these rods are provided with 40 a thumb-nut, and the hooks upon the inner ends are bent in opposite directions, so that they engage with the opposite ends of the springs, and when the ends of the arms are forced apart the rods are drawn in opposite 45 directions and the spring between them is compressed. As soon as the force is removed the spring expands and draws the rods and the arms into their normal position again. Secured upon the outer end of the knotter-shaft 50 is an irregular-shaped cam, 54, which engages with the pins 47 and 48 and communicates motion to the shafts 30 and 31 and the compressors upon them through the segments 32 and 33. One half of the cam 54 keeps the compressors together while the sheaf is being 55 bound by pressing against the pin 47 and holding it down while the arm 45 is in a forward position, and the other half of it keeps them apart after the sheaf has been bound by pressing against the same pin while the arm is in a rearward position, a loop-shaped curve at the middle of the cam operating upon the pin 48 to turn its arm and the arm 45 in a rearward position.

55 Sliding back and forth along the slots 55 and 56 in the platform is a carrier, which consists of two upright bearing-plates, 57 and 58, se-

cured to guide-pieces 59 and 60, which are secured together above the platform by means of the cross-piece 61, and below it by the cross-piece 62. Secured to the cross-piece 61 is an arm or tripper, 63, a spring, 161, having a hook at its end, and two upwardly-extending arms, 64 and 65. The ends of the arms 64 and 65 are provided with bearings for the guide-rods 66 and 67 of the two upright slightly-curved bunchers or packers 68 and 69. Each of these guide-rods is provided with a coiled spring, 70, which forces the packers (and the grain in front of them) a short distance ahead 80 of the carrier as it moves across the platform, so that the points of the curved arms 35 and 36 can come up between the carrier and the grain. Secured to the tops of the arms 64 and 65, above the bearings for the guide-rods, are 85 the brackets 71 and 72, to the ends of which are pivoted the levers 73 and 74, the lower ends of which levers are connected to the packers 68 and 69 by the links 75 and 76.

Secured to the bearings of the shaft 6 is the 90 bench-shaped support 77, upon the top of which are firmly secured the front ends of two parallel beams, 78 and 79, the rear ends of which are secured to the curved and slotted metallic plate 80, which in turn is secured to 95 the beam 28. Near the front ends of these beams is secured the irregular-shaped cross-piece 81, the ends of which engage with the tops of the levers 73 and 74 as the carrier is drawn back after delivering a gavel of grain 100 to the binder. This causes the packers 68 and 69 to be drawn back as near to the carrier as possible, to permit the next gavel of grain to be placed in position without becoming entangled with them. As soon, however, as the carrier 105 starts toward the binder with the gavel the pressure of the cross-piece 81 against the tops of the levers 73 and 74 is removed, and the springs 70 force the packers ahead of the carrier, as described above. The top of a lever, 110 82, pivoted to the bench 77, engages with the hooked spring 161 of the carrier and keeps it from gradually working toward the knotter until it is released by the movement of the clutch 12, which engages with the lower end of 115 the lever when it is moved over by the shaft 6 to put the binding mechanism in motion.

Secured to one of the beams at the same place as the cross-piece 81 is the short upright 83, having a spindle or wrist-pin at its top, upon 120 which swings the A-shaped lever 84. One end of a long connecting-rod, 85, is pivotally connected to the center of the A-lever, and its other end is connected with an arm of a bell-crank lever, 86, which is secured to the middle of the beam 28. Bolted to the other arm of the lever 86 is a flat curved arm, 87, the end of which is forked and passes through a slotted guide-piece, 88, one end of which is secured to the ends of the beams 78 and 79, and the other end 125 is journaled upon the knotter-shaft. The forked end of the arm 87 is kept in an elevated position by means of a coiled spring, 89, which is secured to the A-lever and to a pin upon 130

the end of one of the beams; but when the carrier returns to the forward part of the platform, after a sheaf has been bound, one of the bearing-plates, 57, strikes one of the legs 163 of the A-lever and moves it, so that motion is imparted to the lever 86, which swings the end of the arm 87 down over the compressor 37. As the arm passes down it straddles the binding-cord 90 and lays it in position for the next 10 sheaf. A device for taking up the slack of the binding-cord is secured to the front part of the beams 78 and 79, and consists of a grooved pulley, 91, having a perforation diametrically through it, and having a cogged pinion, 92, 15 at its side, and journaled in a bearing in the bracket 93. This pinion and pulley are operated by the cogged rack 94 at the end of the eccentric-rod 95, which in turn is operated by the cam 96 upon the knotter-shaft. The rear 20 end of the rack 94 has a reduced portion, which slides through a perforated ear, 98, of the plate 99, and its intermediate portion slides within the lips 100 upon the sides of the plate, said plate being rigidly secured to the rod 95. A 25 coiled spring, 101, around the reduced portion keeps the rack forced as far forward as possible relative to rod 95. The rear end of the eccentric-rod 95 is forked, and slides back and forth upon the knotter-shaft, and is provided 30 with a lug, 102, against which the cam 96 operates. The binding-cord passes from the spool in the front part of the machine, through the hole in the pulley, down through a hole in the platform, back to the rear portion of the 35 platform, through an eye, 103, and through the perforations in the needle up to its point and from there to the holder, where it is secured. As the point of the needle begins to rise, the cam 96 begins to operate the pulley 91, which 40 winds up the slack caused by small gavels of grain. If, however, the gavel be full-sized there will be no slack, and the strength of the cord will prevent the pulley 91 from being turned, which in turn will hold the rack 94 45 stationary, and the movement of the bar 95 will be taken up by the compression of the spring 101.

Pivoted to the under side of the platform, with one of its ends projecting over the slot 50 55, is a lever, 104, the other end of which is connected to a rod, 105, which in turn connects with an arm, 106, which is loosely journaled upon the shaft 30, between the shouldered collars 107 and 108. The arm 106 is provided 55 with the lugs 109 and 110, which engage with the shoulders upon the collars 107 and 108, so that as the carrier moves back toward the binding mechanism it engages with the lever 104, and through its connections rotates the 60 shaft 30 sufficiently to raise the points of the needle if the other driving mechanism should be a little tardy in operating. A spring, 111, keeps the end of the lever 104 drawn back out of the way of the carrier as it returns to the 65 front part of the platform.

A drive-chain, 112, runs over the sprocket-wheels 113 and 114 upon the under side of the

platform and conveys motion through a pinion secured to 114 to a large wheel, 116, which is journaled in bearings at the rear of the platform. A short slotted arm, 117, has one end 70 pivotally secured to the chain 112 by means of a lug, 118, which is rigidly secured thereto, and the other end to the cross-piece 62 by means of a nutted bolt, 119, passing through 75 a slot, 120, in the cross-piece and through the slot in the arm 117. By this arrangement the arm 117 can pass between the cross-piece and the sprocket-wheels, and at the same time give 80 a positive motion to the carrier in either direction.

Firmly secured to the large wheel 116 is a small sheave-wheel, 121, which conveys motion to the binding mechanism through the chain 122, and another wheel, 123, secured 85 upon the end of the knotter-shaft. The chain 122 passes over friction-pulleys at the side of the platform.

Secured in bearings upon the upper side of the plate 80 is a bolt, 124, one end of which is 90 beveled and projects over the slot 125 in the plate and the other end is secured to the lever 126. One end of this lever is pivoted to the end of one of the beams and the other end is operated by the cam 127, secured upon the 95 knotter-shaft. As the needle rises to bind a sheaf, it passes through the slot 125 and engages with the beveled portion of the bolt and pushes it back out of its way. A spring, 128, pushes the bolt out across the slot behind the 100 needle as soon as it passes, and keeps it from being pushed back as the sheaf is being compressed and bound, thus taking the strain off the operating mechanism. As soon as the sheaf is bound, and the needle ready to assume 105 its horizontal position, the cam 127 operates against the end of the lever 128 and draws the bolt back, and keeps it back until just before the next sheaf is bound, thus preventing it from interfering with the movement of the 110 curved arm 87. After the sheaf has been bound it is thrown from the platform by two ejector-arms, 129, which are secured to the knotter-shaft.

Pivoted to the rear of the platform and kept 115 in a vertical position by the coiled spring 130 is a board, 131, which is even with the rim around the platform, and against which the grain bears as it is being brought around by the rake and kept from becoming entangled. 120 with the cord and layer. After the sheaf is bound this board is swung down by the sheaf, which is pushed off over it by the ejector-arm. As soon as the pressure is removed the board is brought into a vertical position by the coiled 125 spring 130, where it remains until it is again pressed down by the bound sheaf. Near the forward part of the platform an adjusting-board, 162, is pivotally secured by means of the bracket 133, and adjusted in the desired 130 position by means of a pin upon its underside fitting in the series of holes 134 in the platform.

Secured to one of the brackets 26 is a shield,

135, which prevents the grain from becoming entangled in the cogged segments and the operating-chain. A flexible shield, 136, is secured in a vertical position between the rake-stand and the sickle-bar, which is bent around the stand by the rake as it sweeps the platform, and which compresses the gavel of grain and also keeps it from becoming entangled in the carrier. Two inclined metal plates, 137 and 138, are secured to the platform alongside of the slots 55 and 56, which cause the grain to pass over the slots and the points of the curved arms 35 and 36 without catching upon them.

15 Pivoted secured to the beam 28, at the rear of the platform, is a bundle-carrier, consisting of a shaft, 139, journaled in bearings at its ends, and provided at suitable distances with curved arms 140, the lower ends of which rest upon the step-like projection 141 when the carrier is receiving its load. These arms can be strengthened or braced by means of a cross rod or wire, 142. The rod or shaft 139 is further provided with a short arm, 143, to the 25 end of which is connected the end of a rod, 144, which extends to the front of the machine and is secured to the lever 145, which is pivoted to the angle-iron 146 at its lower end, while its upper end can be operated by the driver 30 and the bundles dropped as desired. This angle-iron 146 is provided with a slot, 147, at its end, by which the platform can be raised or lowered, as required.

Surrounding the grain-platform is a wide 35 board or rim, 148, near the middle of which is secured a post, 149, which has a bearing at its top for one end of the swinging presser-board 150. The other end of this board is journaled in a suitable bearing in the rake-stand, so that it is thus supported across the platform and presses the grain down as the rake sweeps it under it. When grain is 45 fully ripe the stalk will crook over just below the head, so as to make the head hang down or stand at nearly right angles to the stalk, and as the sap is out of the stalk at that time when the grain falls upon the platform there is not weight enough in it to keep the top of the sheaf from being so bushy as to become 50 caught in the binding mechanism if it were not pressed together by this board. The same would be the case with down or tangled grain. A shield, 151, at the post 149 and a flange or wing, 152, upon the end of the board prevent 55 the heads of the grain from becoming entangled or caught upon the post, as they will bear against the wing 152 and be carried along with it as the board is swung upon its pivots until they are beyond the post and pass out from 60 under the board. An arm, 153, secured to the outer end of the board, strikes against a pin, 154, on the side of the rim 148, and causes the board to always stop in the same position after it has been raised by the rake passing underneath it.

At the forward end of the rim 148, and just at the rear of the grain-board, are journaled

two rollers, 155 and 156, the lower one of which is grooved or provided with a pulley, 157, at one end. Running over these rollers 70 is an endless belt or apron, 158, which keeps "lodged" or tangled grain from catching and gathering at that point. The rollers and belt are operated by means of a drive chain or rope, 159, which passes over friction-pulleys at the 75 end of the platform and along just behind the cutter-bar to a point nearly in the rear of the drive-wheel and over friction-pulleys at this point to a larger pulley, 160, secured to the 80 shaft of the drive-wheel.

When enough grain has fallen upon the platform of the reaper to make the desired sized sheaf, the rake is put in operation by the driver, which sweeps the grain around onto the binder-platform. As the rake comes 85 around with its load it presses back the top of the trip-lever, and through its connections moves the main driving-shaft longitudinally in its bearings and sets the binding mechanism in motion.

As soon as the gavel is deposited by the rake the carrier takes it back to the compressor-arms, where it is bound into a sheaf by the knotter. The carrier is returned to its position at the front of the platform, and the sheaf 95 is thrown into the bundle-carrier by the ejector-arms, and the cord placed in position for the next sheaf by the cord-layer. When the carrier arrives at the front part of the platform the tripper pushes the retaining-spring out of the 100 groove around the main shaft, which permits it to be moved longitudinally in its bearings by the coiled spring around it, thus disengaging it from the binding mechanism and stopping the same. When another sheaf is to be 105 bound the same operation, above described, is repeated.

Having thus described my invention, I claim and desire to secure by Letters Patent of the United States—

1. The combination of a binder-platform having a series of slots across it and an operating-shaft journaled in bearings across the front portion, an upright lever secured near each end of said shaft, the middle portion of one of them engaging with a collar upon it, a rod connecting said levers, a spring upon said rod, a collar around said shaft, having an adjusting-arm and secured to one of the bearings, a spring around said shaft between said collars, 115 an annular groove around said shaft, a spring 120 engaging therewith, a carrier sliding in said slots, having a tripper secured thereto operating to throw said spring out of engagement with said shaft, mechanism for operating said carrier, a clutch upon said shaft engaging with said mechanism, a rake, and a binder, as shown and described.

2. The combination of a binder-platform provided with slots, an operating-shaft, and a 130 carrier sliding in said slots, said carrier consisting of two guide-pieces, cross-pieces connecting said guide-pieces above and below the platform, two upright bearing-plates and two

upwardly-inclined arms secured thereto, two packers having guide-rods sliding in bearings in said arms, a spring upon each guide-rod, a bracket secured to the top of each arm, a lever pivoted to each of said brackets, and a link connecting each lever with one of the packers, a stationary cross-piece engaging with the tops of said levers, mechanism for operating said carrier, and a clutch upon said operating-shaft engaging with said mechanism, as shown and described.

3. The combination of a binder-platform provided with slots, an operating-shaft, and a carrier, two shafts journaled across the rear of said platform, one of which has a cogged segment rigidly secured upon one end and two curved arms at its intermediate portion, and the other shaft has a cogged segment loosely secured upon its end and an arm at its intermediate portion, said second segment being provided with two arms, each having a pin at its end, a collar rigidly secured upon the end of said second shaft, provided with an arm, two hooked rods and a coiled spring connecting said arm and one of the arms of said segment, a knotter-shaft journaled in brackets and having an irregular-shaped cam secured upon its end engaging with said pins on the segments, and a chain for operating said knotter shaft, as shown and described.

4. The combination of a binder-platform provided with slots, an operating-shaft, and a carrier, two shafts journaled across the rear of said platform, one of which has two curved arms secured thereto, an arm secured to the other shaft, an auxiliary compressor sliding vertically between said shafts, a lever pivoted to the under side of said platform, engaging with said auxiliary compressor, a lever pivoted to a bracket having a lug upon its intermediate portion, a rod connecting said levers, and a cam upon the knotter-shaft engaging with said lug, as shown and described.

5. The combination of a binder-platform provided with slots, an operating-shaft, and a carrier, a shaft journaled across the rear end of said platform, two shouldered collars secured upon said shaft, an arm loosely journaled between said collars and provided with lugs, a spring-actuated lever pivoted to said platform with one end projecting across one of said slots, and a needle or binder arm, a rod connecting said lever and said arm, as shown and described.

55 6. The combination of a binder-platform provided with a carrier, a bench-shaped support at the front end, and a beam secured upon brackets at the rear end, two parallel beams and a slotted plate connecting said support and beam, a bell-crank lever secured upon the beam having a curved arm secured to one of its arms, the end of said curved arm being forked, an A-lever secured to one of said parallel beams, a pin upon the end of one of said beams, a spring secured to said pin and to one

arm of said A-lever, the other arm of said A-lever being adapted to be operated by a bearing-plate of said carrier, and a rod connected at one end to the middle portion of said A-lever and at the other end to said bell-crank lever, as shown and described.

7. The combination of a binder-platform, a beam secured above said platform, a bracket secured thereto, a shaft journaled in said bracket, a perforated pulley and a cogged pinion secured upon said shaft, an eccentric-rod having its rear end bifurcated and a rack-bar secured to its front end, said rack-bar being movably secured to said rod and provided with a spring, and a cam upon the knotter-shaft operating said eccentric-rod, as shown and described.

8. The combination of a binder-platform provided with slots, an operating-shaft, and a carrier, a lever pivotally secured at the forward portion of said platform and engaging with said shaft, and a hooked spring on said carrier engaging with said lever, as shown and described.

9. The combination of a binder-platform provided with a carrier and an operating-shaft and having two brackets secured at its rear end, a beam connecting said brackets, a slotted plate secured to said beam, two parallel beams secured to said plate at one end and to a support at the other, a spring-actuated bolt having a beveled end secured in bearings at one side of said plate and projecting across said slot, a lever secured to said bolt, a cam upon the knotter-shaft engaging with said lever, and a shaft journaled across the rear of said platform, having a curved arm secured thereto engaging with said bolt, as shown and described.

10. The combination of a harvester-platform, a rim around part of the same, a post secured thereto having a bearing at its top, a pin near the middle of said post and a shield near its top, a swinging presser-board secured in said bearing in said post and in a bearing in the rake-stand, a shield secured to the end of the board, and a downwardly-projecting arm secured to the outer end of said board and a rake, as shown and described.

11. The combination of a binder-platform provided with a carrier having vertical bearing-plates, two shafts journaled across said platform, one of which is provided with two curved arms near its middle portion, the lower part of each arm being provided with a rounded projection, and a knotter, as shown and described.

In testimony that I claim the foregoing as my own I have hereunto affixed my signature in presence of two witnesses.

CHARLES MILLER.
